CLAIM

The ornamental design for a bathroom accessory holder, as shown and described.

DESCRIPTION

FIG. 1 is a top perspective view of the preferred embodiment of the bathroom accessory holder of the present invention.

FIG. 2 is a bottom view of the bathroom accessory holder of FIG. 1.

FIG. 3 is a perspective view of the bathroom accessory holder of FIG. 1.

FIG. 5 is a perspective view of the bathroom accessory holder of FIG. 4, showing a bottom handle portion of a bathroom accessory tightly clamped into place by the plurality of protrusions in the cavity of the bathroom accessory holder; and,

FIG. 6 is a side view of the bathroom accessory holder of FIG. 1.

The broken lines showing a bathroom accessory in use with the bathroom accessory holder is for illustrative purposes only and forms no part of the claimed design.
